ENGINE STARTER

Application filed June 17, 1927. Serial No. 199,596.

This invention relates to apparatus for starting an internal-combustion engine, and more particularly to that type of apparatus which includes an electric motor operating a shaft which is normally disconnected from the engine, but may be connected therewith by means including a pinion movable along the shaft into engagement with the gear of an engine to be started and to rotate with the shaft, said connected means including provisions whereby the pinion will be automatically demeshed from the engine gear when the engine becomes self-operative.

One object of the present invention is to minimize wear and breakage of the gear teeth by providing manually operable means of simple and economical construction for moving the pinion axially into engagement with the engine gear and for rotating the pinion in case of gear tooth abutment in order that the pinion may be nearly fully meshed with the engine gear before the motor is operated.

In our copending application Serial No. 145,318, filed October 30, 1926, we disclosed engine starting apparatus comprising a motor driven, helically-splined shaft upon which an internally helically-splined pinion is slidable into engagement with the gear of an engine to be started. The ends of the pinion teeth remote from the engine gear are so shaped as to provide an annular row of clutch teeth adapted to cooperate with similar clutch teeth formed in one end of a tubular sleeve member slidable along the motor shaft. The sleeve member is moved along the shaft by a manually operated member which closes the motor switch after the pinion has been meshed with the engine gear. The connections between the sleeve member and the manually operated member are provided by a pin in one member cooperating with a slot in the other member, said slot extending obliquely to the axis of the shaft. Movement of the manually operable member is therefore capable of causing the sleeve to rotate as well as to move endwise along the shaft. As it is desirable that the tendency of the sleeve to move endwise should predominate at least until the pinion is moved into contact with the engine gear so that sleeve may be rotated by the man-

ually operable member to the fullest extent in case of gear tooth abutment, friction devices are provided for the purpose of resisting rotation of the sleeve while permitting it to move endwise.

The present invention aims particularly to improve the means for resisting rotation of the sleeve so as to render the apparatus more certain and constant in performance.

Further objects and advantages of the present invention will be apparent from the following description, reference being had to the accompanying drawings wherein a preferred embodiment of one form of the present invention is clearly shown.

In the drawings:

Fig. 1 is a fragmentary view partly in longitudinal section showing a form of engine starting apparatus embodying the present invention, the apparatus being shown in normal position in which the motor pinion is disconnected from the engine gear;

Fig. 2 is a sectional view on the line 2—2 of Fig. 1;

Fig. 3 is a plan view of a sheet metal punch used to form one of the elements of the apparatus shown in Fig. 1;

Fig. 4 is a view similar to Fig. 1 showing the apparatus in condition for starting the engine;

Fig. 5 is a view similar to Fig. 1 showing the apparatus after the engine has become self-operative, but before the manually operable member which controls the starter has been returned to normal position; and

Fig. 6 is a fragmentary sectional view of the pinion retaining means, on a larger scale than the other views.

Referring to the drawings, 20 designates the field frame of an electric motor which is attached by any suitable means not shown to a housing 21. The field frame 20 and the housing 21 support a shaft 22 which is operated by the electric motor, said shaft 22 usually being an extension of the motor armature shaft. The shaft 22 is provided with spiral splines 23 and that portion of the splines 23 which is located between the lines 23^a and 23^b in Fig. 1 is slightly smaller in diameter than the diameter of the remaining

spirally splined portion. The shaft 22 is provided with an annular groove 24, which receives the wire split ring 25. The shaft 22 cooperates with thrust washer 26 bearing 5 against a machined surface 27 provided by the housing 21.

A driving member or pinion 30, which is provided internally with spiral splines, is mounted to slide longitudinally along the 10 shaft 22 into engagement with a rotatable member or flywheel gear 31 of an engine to be started. Normally the pinion 30 is out of mesh with engine gear 31 and is supported by that portion of the splines 23 which is of 15 smaller diameter, namely that portion located between the lines 23^a and 23^b. The splined portion of smaller diameter is connected with the splined portion of larger diameter by shoulder portions 32, which serve as obstructions 20 tending to prevent drifting of the pinion into engagement with engine gear while the engine is running. When the pinion is in full mesh with the engine gear, the wire split ring 25 will be received by an annular groove 25 provided on the interior of the pinion hub. 25 As the pinion 30 is moved toward the right of the drawings into engagement with the ring 25, said ring is first engaged by an annular abutment 34 of smaller internal diameter 30 than the normal external diameter of the ring 25. As the pinion is forced against the ring, the ring will be contracted slightly in order that the obstruction 34 may pass over it. Then the ring will expand into the groove 35 33 as shown in Fig. 6. When the engine becomes self-operative and the pinion is automatically demeshed from the engine gear, the ring 25 will contract again to permit the obstruction 34 to pass beyond it. In this way 40 the pinion 30 is yieldingly maintained in substantially full mesh with the engine gear 31 so that, during the engine cranking operation, axial movement of the pinion, due to momentary reversals in the direction of force 45 transmission between the pinion 30 and the gear 31, will be practically eliminated. These reversals are noticeable particularly in engines having relatively few cylinders and occur when the pistons move past maximum 50 compression. It is therefore apparent that the ring 25 serves as a stop, limiting the movement of the pinion 30 toward the right of the drawings and also as a member for yieldingly maintaining the pinion in full 55 mesh with the engine gear.

The housing 21 supports a bolt or stub shaft 40 which provides a journal for the hub 41 of a manually operable lever 42. The arm 42^a of the lever 42 is so located as to engage the 60 plunger 43 of a starting motor switch 44, the casing 45 of which is secured to the field frame 20 by screws 46. The lever arm 42^a is connected with a pedal 47, which extends through a cup-shaped member 48 carried by 65 the floor board 49 of the automobile. A

spring 50, which is located between the member 48 and the head of the rod 47, tends to maintain the lever 42 in the position shown in Fig. 1.

In order that the pinion 30 may be moved into mesh with the engine gear 31 before the 70 motor switch is closed, means are provided for transmitting motion from the lever 42 to the pinion 30 so that the pinion will be moved endwise into mesh with gear 31 and will be rotated in case the teeth of the pinion collide with the end faces of the teeth of the gear 31, said means being so constructed and arranged that the motor switch cannot be closed until the pinion has been substantially meshed with the engine gear, and so that there will be no interference with demeshing of the pinion from the engine gear after the engine starts, although the lever 42 may still be maintained in operating position. The motion transmitting means comprise chiefly two members, an actuator member and a pinion engaging member, which are connected for movement together longitudinally of the shaft so that one of the members may engage the pinion 30 to move it into mesh with the gear 31, the connection between said members being such that in case motion of the pinion is arrested by the engine gear, one of the members will impart rotary motion to the other member which engages the pinion. The pinion engaging member and pinion provide axially engaging clutching devices so that the rotary motion produced by motion transmitting means will be imparted to the pinion. The actuator member for the pinion engaging member is provided by an actuating pin or stud 51 which is attached to the arm 42^b of the actuating lever 42, and the pinion engaging member is a sleeve 52 which is provided with a slot 53 located obliquely to the axis of the shaft 22 and adapted to receive the pin 51. The sleeve 52 may also be termed an engagement-producing member since it moves the pinion 30 axially into contact with the engine gear 31 and rotates the pinion when necessary to effect driving engagement with the gear.

The sleeve 52 is provided with teeth 54 which function as a driving clutch member for 115 axially engaging a driven clutch member provided by beveling, as shown at 55 in Fig. 4, the ends of the teeth of the pinion 30 in order to provide clutch teeth 56. In the particular form of the invention shown in the drawings 120 the pinion is a nine tooth pinion and hence is provided with nine clutch teeth 56. The sleeve 52 may be provided with nine teeth 54, but, if it is desirable to reduce the maximum of lost rotary motion between the clutch members, the sleeve may have a multiple of the number of teeth 56, for example eighteen teeth, as shown.

The sleeve 52 is formed preferably from a 130 blank or punching of flat sheet material as

shown in Fig. 3. The blank is provided initially with the teeth 54 and the slot 53 and with a dovetail tang 57 adapted to be received by dovetail notch 58. The blank shown in Fig. 3 is formed into a cylinder, the tang 57 being received by the notch 58 in order to prevent opening the joint of the cylinder. The sleeve 52 is supported by a hub 60 carrying spaced discs 61 and 62 which define an annular space 63 which may receive one end of the pin 51. The disc 62 is provided with a circular row of spaced holes 64 each for receiving a tang 65 provided by the sleeve 52, each tang 65 being riveted against the disc 62 as shown in Fig. 1.

The method of using the invention is as follows:

Normally the starting apparatus is in the position shown in Fig. 1 in which the pinion 30 is demeshed from the engine gear and the motor switch is open. To start the engine the pedal 47 is depressed thereby causing the lever 42 to rotate counter-clockwise in order to move the pin 51 and the sleeve 52 longitudinally of the shaft and to the right of the drawings. Due to the use of means to be described for resisting rotation of the sleeve initially while permitting it to move longitudinally, the sleeve 52 will move toward the right and the clutch teeth 54 will engage the clutch teeth 56 provided by the pinion 30. In case the pinion teeth abut the ends of the gear teeth, motion of the sleeve 52 will be arrested; but, if the operator continues to press the pedal 47, the pinion 30 will be rotated due to the cooperation of the pin 51 with the edge 53^a of the oblique slot 53 of the sleeve. The edge 53^a constitutes camming means provided by the sleeve or engagement-producing member 52 cooperating with the actuator or pin 51 so that movement of the actuator along the shaft 22 will tend to rotate the member 52 and to move it axially into co-action with the driving member or pinion 30. When the pinion teeth register with the gear tooth space of the gear 31, the pinion 30 will move into mesh with the gear 31. After the pinion has been nearly meshed with the gear 31, the lever arm 42^a will engage the switch plunger 43 and the motor switch 44 will be closed as shown in Fig. 4. When this occurs, the shaft 22 will be rotated in a clockwise direction as viewed from the right of the drawings and as indicated by the arrows 70 in Figs. 1 and 4, thereby causing the pinion 30 to be moved away from the sleeve 52 and into engagement with the ring 25. Then the pinion 30 will rotate with the shaft 22 and the engine gear 31 will be rotated to crank the engine.

When the engine becomes self-operative the pinion will be automatically demeshed as shown in Fig. 5. Demeshing will occur although the operator may maintain pressure upon the pedal 47, as it is apparent from

Figs. 4 and 5 that the sleeve 52 is free to move toward the left in order not to interfere with the demeshing of the pinion. While the pin and slot connections between the sleeve and the lever permit movement of the sleeve by 70 the pinion when the pinion is demeshed from the engine gear, this operation does not always occur. It happens more frequently that the sleeve 52 is returned to normal position before the engine becomes self-operative. 75 This feature of the invention is due to the fact that there is always some friction between the sleeve hub 60 and the shaft 22; therefore when the shaft 22 is operated by the motor, the hub 60 and sleeve 52 will be 80 rotated in the direction of the arrow 70 while the pin 51 is maintained in the position shown in Fig. 4. Consequently the rotation of the shaft 22 before the engine becomes self-operative will cause the sleeve 52 to be 85 threaded along the pin 51 and to be moved into the retracted position shown in Fig. 5. Therefore demeshing of the pinion 30 will take place without any engagement between the clutch teeth 54 and 56. The edge 53^b of 90 the oblique slot 53 therefore constitutes a camming means provided by the sleeve or engagement-producing member 52 and cooperating with the actuator or pin 51 in a manner such that, while the pin remains stationary and the sleeve 52 is rotated due to frictional engagement with the shaft 23, the sleeve 52 will be automatically retracted from the driving member or pinion 30 and will be moved to normal axial position relative to the shaft 23.

After the operator releases the pedal 47, the spring 50 will be released to move the pedal upwardly and to return the lever 42 to the position shown in Fig. 1. During this operation a spring 43^a will be released to move the switch plunger 43 from the position shown in Fig. 4 to that shown in Fig. 1 in order to open the motor switch.

Means cooperating with the sleeve 52 and the shaft 22 are provided for resisting the tendency of the sleeve to rotate just at the beginning of its movement from non-operating position, or toward the right from the position shown in Fig. 1. This means comprises a metal brake disc 80 fixed to the shaft 22 a floating disc 81 of yieldable material, such as cork, and a brake disc provided by the flange 82 of the disc 62. The parts 80, 81 and 82 are maintained normally in engagement by the spring 50 which urges the lever arm 42^b toward the left as viewed in Fig. 1. Hence, normally, the brake members 80, 81 and 82 tend to maintain the sleeve fixed relative to the shaft 22. When the lever arm 42^b begins its movement toward the right, the brake members are apparently not instantly disengaged, but tend to resist rotation of the sleeve 52 after the sleeve has begun to move toward the right. Apparently

the cork disc 81 expands axially sufficiently to maintain friction between the brake members after motion of the sleeve has begun. Since resistance to endwise movement of the sleeve is overcome before removing resistance to rotation of the sleeve, the tendency of the sleeve to move endwise will be greater, initially, than the tendency for the sleeve to rotate. Hence the possibility of the sleeve rotating without moving endwise has been reduced.

The brake members 80, 81 and 82 cooperate with the pinion shifting mechanism for the further purpose of bringing the motor shaft 22 quickly to rest after the operator releases the pedal 47. It is apparent that the spring 50 will urge the brake member 82 toward the brake members 81 and 80. Since the brake member 82 is prevented from rotating freely with the shaft 22 by reason of engagement of the pin 51 with the sleeve 52, the brake disc 82 will function as a stationary brake member cooperating with the movable brake disc quickly to arrest motion of the shaft 22. In case the engine should make a false start, that is, if the engine should become self-operative for a time sufficient to demesh the pinion 30 from the gear 31 but should not continue to be self-operative, the operator will not need to wait for a substantial period to elapse for the motor shaft to stop rotating before repeating the pinion shifting operation. In case of a false start, the operator may release the pedal to restore the gear shifting mechanism to normal condition, and then may almost immediately depress the pedal to repeat the starting operation.

A means for resisting rotation of the engagement-producing member or sleeve 52 during a substantial part of its movement from normal toward the pinion 30 comprises a plunger 90 guided by a recess 91 in the housing 21 and pressed by a spring 92 against a lug 93 carried by the disc 62. As shown in Fig. 2, the lug 93 provides cylindrical surfaces 93^a and 93^c concentric with the sleeve 52 but of different radii. These surfaces are joined by an oblique surface 93^b providing a longitudinally extending shoulder. Surface 93^c merges into a surface 93^d of different curvature and center of curvature the end portion of which is nearer to the sleeve than the inner end of the plunger 90 when the lug is moved away from it. Normally the plunger 90 bears against the surface 93^a. Movement of the pin 51 toward the right in Fig. 1 tends to turn the sleeve clockwise as viewed in Fig. 2, but this movement is resisted by friction between the end of the plunger 90 and the surface 93^a, also by friction between the plunger 90 and the surface 93^b in case the sleeve turns to permit this, and also by the increase in resistance of the spring 92 in case the surface 93^b cams the plunger 90 toward the right as viewed in

Fig. 2. The surfaces of the lug 93 are parallel to axis of the sleeve 52 to permit endwise movement of the sleeve. When the sleeve has moved sufficiently to cause the pinion 30 to contact with the engine gear 31 the lug 93 will have been moved away from the vertical plane of the plunger 90, so that the sleeve may be freely rotated in case of gear tooth abutment.

After the engine becomes self-operative and before the pedal 47 has been released as shown in Fig. 5, the sleeve 52 will have been moved into such position that the lug 93 is approximately vertically below axis of the sleeve 52. When the pedal 47 is released the spring 50 will restore the sleeve 52 to the position shown in Fig. 1. As the pin 51 moves toward the left of the drawings, the sleeve 52 will be rotated counterclockwise as viewed in Fig. 2 due to the coaction between the pin 51 and the edge 53^b of the slot 53. As the lug 93 rotates in this direction the surfaces 93^a, 93^c, 93^b and 93^d successively engage the plunger 90. It will be noted that the surface 93^a, as it extends away from the surface 93^c, is located more closely to the axis of the sleeve 52. As the edge of surface 93^d rotates past the end of plunger 90 counter-clockwise as viewed in Fig. 2, the end of the plunger 90 will be caught by surface 93^d and will be cammed upon the surface 93^c, and will thereafter be permitted to ride down upon the shoulder 93^b and to rest finally upon the surface 93^a. The slot edge 53^b therefore constitutes a camming means which coacts with the actuator or pin 51 in such manner that when the pin 51 is restored to normal position, the sleeve or engagement-producing member 52 will be restored to normal position angularly relative to the shaft 22 and the rotation resisting device provided by the plunger 90 and the shoulder 93^b will be restored to normal operativeness.

In case of back-fire during the gear meshing operation, the pinion will be moved toward the right from the position shown in Fig. 4, and out of engagement with the sleeve clutch teeth.

From the foregoing description of the construction and the mode of operation of the present invention, it will be apparent that the invention possesses the advantages of simplicity and durability of construction and reliability of operation. The number of parts required for the starter drive is very small and they may be constructed and assembled at very low cost. Owing to the simplicity of construction the parts may be made relatively rugged and substantial and therefore very durable. With this form of invention the starter pinion is meshed with the engine gear before the motor is operated, hence liability of danger to the gear teeth has been substantially reduced. The pinion may be demeshed from the engine gear auto-

matically, thus avoiding the necessity of an over-running clutch to permit disconnection of the engine for the motor armature shaft when the engine becomes self-operative.

5 Since the starter drive provides no obstruction to the demeshing movement of the pinion the apparatus will be relatively quiet in operation.

10 While the form of embodiment of the present invention as herein disclosed, constitutes a preferred form, it is to be understood that other forms might be adopted, all coming within the scope of the claims which follow.

What is claimed is as follows:

15 1. Engine starting apparatus comprising, in combination, a motor; a shaft operated by the motor; means for connecting the shaft with the gear of an engine to be started and including a pinion mounted on the shaft for longitudinal movement thereof and rotary movement therewith and provisions whereby the pinion will be automatically demeshed from the engine gear when the engine starts; means for shifting the pinion endwise into 20 mesh with the engine gear and for rotating the pinion in case the pinion teeth collide with the engine gear teeth, said means including a sleeve movable along the shaft and provided with slot oblique to the shaft, and 25 a pin movable longitudinally of the shaft and engaging the slot, whereby the pin and sleeve may move together to move the pinion into mesh with the engine gear and whereby the sleeve may be rotated in case movement thereof is obstructed, said sleeve and pinion having clutching means for imparting rotation to the pinion; and means tending frictionally to resist rotation of the sleeve during a substantial portion of the movement of the sleeve toward the pinion, said means being inoperative while the pinion is rotated by the sleeve in case of gear-tooth abutment.

25 2. Engine starting apparatus according to claim 1 in which the sleeve carries a lug of substantial width which is engaged by a relatively stationary, resiliently urged plunger only during a substantial portion of the movement of the sleeve toward the pinion. 30

30 3. Engine starting apparatus according to claim 1 in which the sleeve carries a lug of substantial width which is engaged by a relatively stationary, resiliently urged plunger only during a substantial portion of the movement of the sleeve toward the pinion. 35

35 4. Engine starting apparatus according to claim 1 in which the sleeve carries a lug of substantial width which is engaged by a relatively stationary, resiliently urged plunger only during a substantial portion of the movement of the sleeve toward the pinion, the lug having cylindrical surfaces concentric with the axis of the sleeve joined by an oblique surface, said surfaces being parallel to the axis of the sleeve, the plunger normally engaging the surface of lesser radius, and the surfaces being arranged so that rotation of the sleeve occurring when the sleeve is manually moved toward the pinion, will cause the oblique surface to engage the 40 plunger. 105

40 5. Engine starting apparatus according to claim 1 in which the sleeve carries a lug of substantial width which is engaged by a relatively stationary, resiliently urged plunger only during a substantial portion of the movement of the sleeve toward the pinion, the lug having cylindrical surfaces concentric with the axis of the sleeve joined by an oblique surface, said surfaces being parallel to the axis of the sleeve, the plunger normally engaging the surface of lesser radius, and the surfaces being arranged so that rotation of the sleeve occurring when the sleeve is manually moved toward the pinion, will cause the oblique surface to engage the 45 plunger. 110

45 6. Engine starting apparatus according to claim 1 in which the sleeve carries a lug of substantial width which is engaged by a relatively stationary, resiliently urged plunger only during a substantial portion of the movement of the sleeve toward the pinion, the lug having cylindrical surfaces concentric with the axis of the sleeve joined by an oblique surface, said surfaces being parallel to the axis of the sleeve, the plunger normally engaging the surface of lesser radius, and the surfaces being arranged so that rotation of the sleeve occurring when the sleeve is manually moved toward the pinion, will cause the oblique surface to engage the 50 plunger. 115

50 7. Engine starting apparatus according to claim 1 in which the sleeve carries a lug of substantial width which is engaged by a relatively stationary, resiliently urged plunger only during a substantial portion of the movement of the sleeve toward the pinion, the lug having cylindrical surfaces concentric with the axis of the sleeve joined by an oblique surface, said surfaces being parallel to the axis of the sleeve, the plunger normally engaging the surface of lesser radius, and the surfaces being arranged so that rotation of the sleeve occurring when the sleeve is manually moved toward the pinion, will cause the oblique surface to engage the 55 plunger. 120

55 8. An engine starter drive comprising, a rotatable driving member mounted to move axially into driving engagement with a member of the engine to be started; and manually operated means for moving the driving member axially, and for rotating it when necessary to effect its driving engagement with the engine member, said means including a rotatable engagement-producing member mounted for movement axially of the driving member, actuating means tending both to rotate and to move longitudinally the engagement-producing member, and frictional means including a non-rotatable part tending to resist rotation of the engagement-producing member. 125

60 9. An engine starter drive comprising, a rotatable driving member mounted to move axially into driving engagement with a member of the engine to be started; and manually 130

including a pinion mounted on the shaft for longitudinal movement thereof and rotary movement therewith and provisions whereby the pinion will be automatically demeshed from the engine gear when the engine starts; means for shifting the pinion endwise into mesh with the engine gear and for rotating the pinion in case the pinion teeth collide with the engine gear teeth, said means including a sleeve movable along the shaft and provided with slot oblique to the shaft, and a pin movable longitudinally of the shaft and engaging the slot, whereby the pin and sleeve may move together to move the pinion into mesh with the engine gear and whereby the sleeve may be rotated in case movement thereof is obstructed, said sleeve and pinion having clutching means for imparting rotation to the pinion; and means tending frictionally to resist rotation of the sleeve during a substantial portion of the movement of the sleeve toward the pinion, said means being inoperative while the pinion is rotated by the sleeve in case of gear-tooth abutment. 70

75 6. Engine starting apparatus according to claim 5 in which the sleeve carries a lug of substantial width which is engaged by a relatively stationary, resiliently urged plunger only during a substantial portion of the movement of the sleeve toward the pinion. 80

80 7. Engine starting apparatus according to claim 5 in which the sleeve carries a lug of substantial width which is engaged by a relatively stationary, resiliently urged plunger only during a substantial portion of the movement of the sleeve toward the pinion. 85

85 8. Engine starting apparatus according to claim 5 in which the sleeve carries a lug of substantial width which is engaged by a relatively stationary, resiliently urged plunger only during a substantial portion of the movement of the sleeve toward the pinion, the lug having cylindrical surfaces concentric with the axis of the sleeve joined by an oblique surface, said surfaces being parallel to the axis of the sleeve, the plunger normally engaging the surface of lesser radius, and the surfaces being arranged so that rotation of the sleeve occurring when the sleeve is manually moved toward the pinion, will cause the oblique surface to engage the 90 plunger. 100

90 9. Engine starting apparatus according to claim 5 in which the sleeve carries a lug of substantial width which is engaged by a relatively stationary, resiliently urged plunger only during a substantial portion of the movement of the sleeve toward the pinion, the lug having cylindrical surfaces concentric with the axis of the sleeve joined by an oblique surface, said surfaces being parallel to the axis of the sleeve, the plunger normally engaging the surface of lesser radius, and the surfaces being arranged so that rotation of the sleeve occurring when the sleeve is manually moved toward the pinion, will cause the oblique surface to engage the 95 plunger. 105

95 10. Engine starting apparatus according to claim 5 in which the sleeve carries a lug of substantial width which is engaged by a relatively stationary, resiliently urged plunger only during a substantial portion of the movement of the sleeve toward the pinion, the lug having cylindrical surfaces concentric with the axis of the sleeve joined by an oblique surface, said surfaces being parallel to the axis of the sleeve, the plunger normally engaging the surface of lesser radius, and the surfaces being arranged so that rotation of the sleeve occurring when the sleeve is manually moved toward the pinion, will cause the oblique surface to engage the 110 plunger. 110

100 11. Engine starting apparatus according to claim 5 in which the sleeve carries a lug of substantial width which is engaged by a relatively stationary, resiliently urged plunger only during a substantial portion of the movement of the sleeve toward the pinion, the lug having cylindrical surfaces concentric with the axis of the sleeve joined by an oblique surface, said surfaces being parallel to the axis of the sleeve, the plunger normally engaging the surface of lesser radius, and the surfaces being arranged so that rotation of the sleeve occurring when the sleeve is manually moved toward the pinion, will cause the oblique surface to engage the 115 plunger. 120

105 12. Engine starting apparatus according to claim 5 in which the sleeve carries a lug of substantial width which is engaged by a relatively stationary, resiliently urged plunger only during a substantial portion of the movement of the sleeve toward the pinion, the lug having cylindrical surfaces concentric with the axis of the sleeve joined by an oblique surface, said surfaces being parallel to the axis of the sleeve, the plunger normally engaging the surface of lesser radius, and the surfaces being arranged so that rotation of the sleeve occurring when the sleeve is manually moved toward the pinion, will cause the oblique surface to engage the 125 plunger. 130

operated means for moving the driving member axially, and for rotating it when necessary to effect its driving engagement with the engine member, said means including a rotatable engagement-producing member mounted for movement axially of the driving member, an actuator movable in the direction of axial movement of the engagement-producing member, means for transmitting motion from the actuator to the engagement-producing member tending to move the latter rotarily and longitudinally, and frictional means including a non-rotatable part tending to resist rotation of the engagement-producing member.

10. An engine starter drive comprising, a rotatable driving member mounted to move axially into driving engagement with a member of the engine to be started; and manually operated means for moving the driving member axially, and for rotating it when necessary to effect its driving engagement with the engine member, said means including a rotatable, engagement-producing member mounted for movement axially of the driving member and provided with a part oblique to its line of axial movement, an actuator engageable with said oblique part to tend both to rotate and to move axially the engagement-producing member, and a non-rotatable part engageable with the engagement-producing member to resist rotation thereof.

11. An engine starter drive comprising, a rotatable driving member mounted to move axially into driving engagement with a member of the engine to be started; and manually operated means for moving the driving member axially, and for rotating it when necessary to effect its driving engagement with the engine member, said means including, a tubular, rotatable, engagement-producing member mounted for movement axially of the driving member and provided with a slot oblique to its line of axial movement, an actuator pin engageable with said slot and movable substantially in the direction of axial movement of the driving member in order to tend both to rotate and to move axially the engagement producing member, and a non-rotatable part engageable with the engagement-producing member to resist rotation thereof.

12. An engine starter drive comprising, a driving shaft, a driving member connected with the shaft for rotary movement therewith and longitudinal movement thereof into driving engagement with a member of the engine to be started; and manually operated means for moving the driving member along the shaft and for rotating it, when necessary, to effect its driving engagement with the engine member, said means including an engagement-producing member movable along the shaft and rotatable independently thereof, actuating means tending both to rotate

and to move longitudinally the engagement-producing member, and friction means including a non-rotatable part tending to resist rotation of the engagement producing member.

13. An engine starter drive comprising, a driving shaft, a driving member connected with the shaft for rotary movement therewith and longitudinal movement thereof into driving engagement with a member of the engine to be started; and manually operated means for moving the driving member along the shaft, and for rotating it when necessary, to effect its driving engagement with the engine member, said means including an engagement-producing member movable along the shaft and rotatable independently thereof, an actuator movable alongside the shaft, means for transmitting motion from the actuator to the engagement-producing member tending to move the latter rotarily and longitudinally, and frictional means including a non-rotatable part tending to resist rotation of the engagement-producing member.

14. An engine starter drive comprising, a driving shaft, a driving member connected with the shaft for rotary movement therewith and longitudinal movement thereof into driving engagement with a member of the engine to be started; and manually operated means for moving the driving member along the shaft, and for rotating it when necessary, to effect its driving engagement with the engine member, said means including a tubular, engagement-producing member movable along the shaft and rotatable independently thereof and provided with a part oblique to the line of axial movement of the driving member, an actuator movable alongside the shaft and engageable with said oblique part to tend to move the engagement-producing member rotarily and longitudinally, and a non-rotatable part cooperating with the engagement-producing member for resisting rotation of the latter.

15. An engine starter drive comprising, a drive shaft; a pinion connected with and movable axially along the shaft into engagement with a gear connected with the engine to be started; and manually operated means for moving the pinion along the shaft, and for rotating it when necessary, to effect driving engagement with the engine gear, said means including an engagement-producing member movable axially of the shaft into contact with the pinion and rotatable independently of the shaft, means rotatively connecting the member and pinion, actuating means tending to rotate and axially move the member, and a non-rotatable part cooperating with the member to resist rotation thereof.

16. An engine starter drive comprising, a drive shaft; a pinion connected with and movable axially along the shaft into engagement with a gear connected with the engine

to be started; and manually operated means for moving the pinion along the shaft, and for rotating it when necessary, to effect driving engagement with the engine gear, said means including a cylindrical engagement-producing member mounted to move along the shaft toward the pinion and having means clutching with the pinion to rotate the latter and having a part oblique to its line of axial movement, an actuator movable along the shaft for engaging the oblique part in order to tend both to rotate and to axially move the member, and a non-rotatable part cooperating with the member to resist rotation thereof.

17. An engine starter drive comprising, a drive shaft; a pinion connected with and movable axially along the shaft into engagement with a gear connected with the engine to be started; and manually operated means for moving the pinion along the shaft, and for rotating it when necessary, to effect driving engagement with the engine gear, said means including a tubular engagement-producing member mounted upon the shaft and movable axially into engagement with the pinion and having an annular row of clutch teeth engageable with the pinion teeth in order to rotate the pinion, said member having a slot oblique to the line of axial movement of the pinion, a pin movable along the shaft and received by the oblique slot whereby the pin tends to rotate and to axially move the member, and a stationary part cooperating with the member to resist rotation thereof.

18. An engine starter drive comprising, a drive shaft; a pinion connected with and movable axially along the shaft into engagement with a gear connected with the engine to be started; and manually operated means for moving the pinion along the shaft, and for rotating it when necessary, to effect driving engagement with the engine gear, said means including an engagement-producing member movable axially of the shaft into contact with the pinion and rotatable independently of the shaft, means rotatively connecting the member and pinion, actuating means tending to rotate and axially move the member, a part connected with the member and providing a longitudinal extending shoulder between surfaces located at different distances from the axis of the member, and a stationary plunger spring urged normally against the surface lying at the lesser distance from the axis of the member and engageable with said shoulder in order to tend to resist rotation of the member.

19. An engine starter drive comprising, a driving shaft, a driving member connected with the shaft for rotary movement therewith and longitudinal movement thereof into driving engagement with a member of the engine to be started; and manually operated means for moving the driving member along

the shaft, and for rotating it when necessary, to effect its driving engagement with the engine member, said means including an engagement-producing member movable along the shaft and rotatable independently thereof, an actuator movable alongside the shaft, means for transmitting motion from the actuator to the engagement-producing member tending to move the latter rotarily and longitudinally, a part connected with the member and providing a longitudinal extending shoulder between surfaces located at different distances from the axis of the member, and a stationary plunger spring urged normally against the surface lying at the lesser distance from the axis of the member and engageable with said shoulder in order to tend to resist rotation of the member.

20. An engine starter drive comprising, a rotatable driving member mounted to move axially into driving engagement with a member of the engine to be started; and manually operated means for moving the driving member axially, and for rotating it when necessary to effect its driving engagement with the engine member, said means including a rotatable engagement-producing member mounted for movement axially of the driving member, actuating means tending both to rotate and to move longitudinally the engagement-producing member, a part connected with the member and providing a longitudinal extending shoulder between surfaces located at different distances from the axis of the member, and a stationary plunger spring urged normally against the surface lying at the lesser distance from the axis of the member and engageable with said shoulder in order to tend to resist rotation of the member.

21. An engine starter drive comprising, a rotatable driving member mounted to move axially into driving engagement with a member of the engine to be started, and providing an axially engageable driven clutch element; a rotatable member providing a driving clutch element axially engageable with the driven clutch of the driving member; means for moving the driving clutch axially toward the driven clutch and for rotating the latter in case its axial movement is obstructed; and friction means including a fixed part tending to resist rotation of the driving clutch.

22. Engine starting apparatus comprising, in combination, a motor; a shaft operated by the motor; means for connecting the shaft with the gear of an engine to be started and including a pinion mounted on the shaft for longitudinal movement thereof and rotary movement therewith and provisions whereby the pinion will be automatically demeshed from the engine gear when the engine starts; and manually operated means for moving the pinion axially and for rotating it, when

necessary, to effect its engagement with the gear, said means including a rotatable, and axially movable engagement-producing member mounted upon the shaft, actuating means tending both to rotate and to axially move the member, and means including a non-rotatable part for frictionally resisting rotation of the member.

23. Engine starting apparatus comprising, in combination, a motor; a shaft operated by the motor; means for connecting the shaft with the gear of an engine to be started and including a pinion mounted on the shaft for longitudinal movement thereof and rotary movement therewith and provisions whereby the pinion will be automatically demeshed from the engine gear when the engine starts; and manually operated means for moving the pinion axially and for rotating it, when necessary, to effect its engagement with the gear, said means including a rotatable and axially movable engagement-producing member mounted upon the shaft, actuating means tending both to rotate and to axially move the member, and means for resisting rotation of the member while the pinion is being moved thereby into contact with the engine gear, said means being inoperative while the member is rotating the pinion.

30 24. Engine starting apparatus comprising, in combination, a motor; means for connecting the motor with the gear of an engine to be started and including a pinion movable axially into engagement with the gear, and provisions whereby the pinion will be automatically demeshed when the engine starts; a rotatable member movable coaxially with respect to the pinion and having means for axially engaging the pinion and for rotating the pinion; actuating means for moving the member into contact with the pinion and the pinion into contact with the gear and for rotating the member to rotate the pinion, when necessary, to effect gear meshing; and means for resisting rotation of the member while the pinion is being moved by said member into contact with the gear, and inoperative while the member is rotating the pinion.

40 25. An engine starter drive comprising, a rotatable driving member mounted to move axially into driving engagement with a member of the engine to be started; an axially and rotarily movable engagement-producing member for moving the driving member axially, and rotatively when necessary, to effect its driving engagement with the engine driven member; an actuator movable along the engagement-producing member; means 45 so connecting the actuator and engagement-producing member that movement of the actuator from normal position tends to rotate and to axially move the engagement-producing member, into coaction with the driving member, and rotation of the engagement-

producing member in one direction while the actuator is relatively stationary causes axial movement of the engagement-producing member away from coaction with the driving member, and return of the actuator to normal position produces rotation of the engagement-producing member to normal position; a power operated rotatable element for turning the driving member and having frictional engagement with the engagement-producing member for turning the same in such direction that it will be axially retracted from coaction with the driving member; and a device for resisting rotation of the engagement-producing member during a part of its movement from normal position into coaction with the driving member, said device being restored to operation by the return rotation of the engagement-producing member to normal position.

50 26. An engine starter drive comprising, a drive shaft; a driving member connected with the shaft for rotary movement therewith and longitudinal movement thereof into driving engagement with a member of the engine to be started; an engagement-producing member journaled upon the shaft and movable axially into coaction with the driving member, and yieldably connected with the shaft so that rotation of the shaft tends to rotate it; an actuator movable along the shaft; means so connecting the actuator and engagement-producing member that movement of the actuator from normal position tends to rotate and to axially move the engagement-producing member into coaction with the driving member, and rotation of the engagement-producing member by the shaft when operating the driving member while the actuator is relatively stationary causes axial retraction of the engagement-producing member from the driving member, and return of the actuator to normal position produces rotation of the engagement-producing member to normal position; and a device for resisting rotation of the engagement-producing member during a part of its movement from normal position into coaction with the driving member, said device being restored to operation by the return rotation of the engagement-producing member to normal position.

55 27. An engine starter drive comprising, a rotatable driving member mounted to move axially into driving engagement with a member of the engine to be started; an axially and rotarily movable engagement-producing member for moving the driving member axially, and rotatively when necessary, to effect its driving engagement with the engine driven member; an actuator movable along the engagement-producing member; camming means connected with the engagement-producing member and coacting with the actuating member so that movement of the ac-

tuating member away from normal position tends to rotate and to axially move the engagement-producing member into coaction with the driving member; a device for resisting rotation of the engagement-producing member during a part of its axial movement into coaction with the driving member; and camming means connected with the engagement-producing member and cooperating with the actuator for restoring the engagement-producing member to normal position and the rotation-resisting-device to normal operation in response to the return of the actuating member to normal position.

15 In testimony whereof we hereto affix our signatures.

WILLIAM A. CHRYST.
GEORGE W. ELSEY.
